UNITED STATES PATENT OFFICE

HARRY M. PFORSICH, OF MONTPELIER, INDIANA, ASSIGNOR TO HUBBARD & COMPANY,
A CORPORATION OF PENNSYLVANIA

SHOVEL

Application filed October 30, 1928. Serial No. 316,007.

This invention relates to shovels and more particularly to shovels manufactured from sheet metal such, for example, as sheet steel or the like.

5 An object of this invention is to provide an improved construction for shovels of this type together with an improved method of manufacturing the same.

These and other objects which will be apparent to those skilled in this particular art are accomplished by means of the invention illustrated in the accompanying drawings in which Figure 1 is a view in elevation of a sheet metal blank from which 15 the shovel is made. Fig. 2 is a side view of the finished shovel blade and socket, and Fig. 3 is a perspective view thereof.

The particular embodiment of this invention which has been chosen for the purposes 20 of illustration includes a blade portion 5 of any desired form or shape, pressed from sheet metal into the desired configuration, the blank 6 having sufficient metal in its upper portion to allow for the formation of 25 the frog 7 in the pressing operation.

Heretofore, sheet metal shovels having tubular socket handles have been formed so that the sockets have extended outwardly 30 from the frog portion in a straight line for receiving straight ended handles. This produces an awkward angle between the handle and the shovel blade which gives an insufficient "lift", rendering the shovel inconvenient to handle and extremely tiring to work with. In the present invention the blank 35 6 has an integral socket arm 8 extending upwardly from the blade portion, and this socket arm portion 8 is pressed around a mandrel in the bending operation into a tubular curved shovel socket 9, integral with the blade 5 and adapted to receive and be secured to the curved end 10 of a handle 11 by suitable rivets 12 or the like. The 40 curved socket 9 includes a portion 13 which 45 extends away from the blade 5 and frog 7

at an abrupt angle and this portion is curved into the outer socket portion 14. The entire socket 9 tapers gradually from a point closely adjacent the frog 7 to the outer end thereof. The blank has ears 15 which co-operate in the finished shovel to carry the closed socket down to a level with the bottom of the blade as indicated at the point 16, eliminating any V opening at the lower end of the socket seam. 50

In the preferred embodiment shown in the drawings, it will be seen that the outer socket portion 14 is straightened to a plane substantially parallel to the plane of the top central portion of the blade 5, see Fig. 2, 55 in order that the "hand force" applied to the handle 11 and the "foot force" applied to the top edge of the blade 5 will be exerted in the most efficient, skillful, and advantageous manner. Further, to avoid the inherent weaknesses of spherical or pointed socket ends, the extreme of the socket 14 is 60 cut along a common plane, thus providing an annular shaped edge. 65

What I claim as new and desire to secure 70 by Letters Patent is:

1. The combination in a shovel of a sheet metal blade, an integral handle receiving socket portion of tubular form angularly curved frontwardly of said blade, the extending end portion of said socket being straightened to a plane substantially parallel to the plane of the top central portion of the back of said blade. 75

2. The combination in a shovel of a sheet metal blade, an integral handle receiving socket portion of tubular form angularly curved frontwardly of said blade, the extending end portion of said socket being straightened to a plane substantially parallel 80 to the plane of the top central portion of the back of said blade, and a handle having a curved end conforming to said socket portion and rigidly secured therein. 85

3. The combination in a shovel of a sheet 90

metal blade, an integral handle receiving
socket portion of tubular form angularly
curved frontwardly of said blade, the ex-
tending end portion of said socket being
5 straightened to a plane substantially parallel
to the plane of the top central portion of
the back of said blade, the edge of the ex-
tending end of said socket portion being cut
on a common plane and conforming to an
10 annular outline, and a handle having a
curved end corresponding to the socket por-
tion and rigidly secured therein.

In testimony whereof, I have hereunto
subscribed my name this 26 day of Oct.,
15 1928.

HARRY M. PFORSICH.
